WORK GUIDING MEANS FOR SHOE
SEWING MACHINESWalter D. Shaffer, Chicago, Ill., assignor to United
Shoe Machinery Corporation, Flemington, N. J.,
a corporation of New Jersey

Application June 9, 1949, Serial No. 98,025

6 Claims. (Cl. 112—51)

1

The present invention relates to work guiding means for machines constructed to sew the outsole to the welted upper and insole of a lasted welt shoe, and more particularly to improvements in sewing machines such as that disclosed in United States Letters Patent No. 2,435,193, granted February 3, 1948 in the name of Fred Ashworth, arranged for preventing the inseam of a Goodyear welt shoe from being cut by the stitch forming devices during insertion of the outsole, particularly along the inside shank of a shoe, and to facilitate proper insertion of the outsole along the sides of the heel portion of the shoe where the projecting marginal portions of the outsole and welt are relatively narrow.

The object of the present invention is to simplify the construction of the edge gage adjusting connections and to render the connections more reliable in operation and more adaptable for the purposes intended than in the patented construction. To this end, the present invention resides in a shoe outsole sewing machine having a work support, a needle, an edge gage and a manually operated member mounted for limited movement during sewing operations to move the edge gage, in which means is provided for stopping the movement of the manually operable member yieldingly at a third position intermediate the limiting positions and for readily making adjustments to permit free movement of the manually operable member past the third position. By providing means for yieldingly stopping the movement of the edge gage adjusting member, effective location of the edge gage is assured without the necessity of providing a positive stop in the third intermediate position, as in the machine of the patent. Thus, it is possible to move the adjusting member without stopping through the intermediate position or not, as required, no further changes in the adjusting connections being needed for the two types of operation. In the preferred form of the invention, the third position stopping means comprises a spring-pressed detent engaging the manually operated adjusting member or a part connected thereto.

These and other features of the invention as hereinafter described and claimed will become apparent from a consideration of the following specification taken in connection with the accompanying drawings, in which

Fig. 1 is a view in right-hand side elevation of a portion of a shoe outsole sewing machine having an edge gage actuating mechanism embodying the features of the present invention;

2

Fig. 2 is a sectional view of a shoe taken along the heel seat during sewing operations;

Figs. 3 and 4 are similar sectional views taken along the shank and forepart of a shoe, respectively;

Fig. 5 is a detail view in front elevation of the edge gage and its adjusting mechanism;

Fig. 6 is a plan view partly in section of the mechanism illustrated in Fig. 5 showing the positions of the parts when the edge gage is moved to extreme rearward position to enable sewing along the heel seat of a shoe as in Fig. 2;

Figs. 7 and 8 are similar sectional plan views of the adjusting mechanism illustrating the positions of the parts assumed while the edge gage is adjusted to an intermediate position for sewing along the shank of the shoe, as in Fig. 3, and to the limit of its foremost position for sewing along the forepart of the shoe as in Fig. 4;

Fig. 9 is a plan view partly in section and on an enlarged scale of the adjusting arm and a strut carrying stopping means for locating the adjusting arm at the intermediate position;

Fig. 10 is a view in elevation of the adjusting arm and the strut;

Fig. 11 is a view in end elevation of the arm and strut;

Fig. 12 is a plan view of a modified form of adjusting mechanism for an edge gage in a shoe outsole sewing machine, illustrating the positions of the parts while the edge gage is at the extreme limit of its rearward movement as illustrated in Fig. 2;

Figs. 13 and 14 are similar views illustrating the positions of the parts with the edge gage in its intermediate position and at the limit of its forward position, as in Figs. 3 and 4, respectively;

Fig. 15 is an enlarged detail view partly in section of some of the operating connections in the modified form of adjusting mechanism shown in Fig. 12;

Fig. 16 is a view in front elevation of the same connections and the hand adjusting lever therefor; and

Fig. 17 is a sectional view of the parts shown in Fig. 15 taken along the line XVII—XVII.

The machine illustrated in the drawings is similar to that of the prior patent above referred to and is intended to sew together an outsole and a welt of a Goodyear welt shoe with a seam extending from the heel seat at one side along the shank to the forepart and then along the other side of the shoe, returning to the heel seat. As in the prior machine the location of the seam is determined in part by an edge gage 20 adjust-

able during sewing operations to one of three positions as shown in Figs. 2, 3 and 4.

In Fig. 4 the outsole of a Goodyear welt shoe is illustrated at 22 in the process of being sewn to a welt 24 connected to a shoe upper 26 and an insole 28 by an inseam 30. In sewing the outseam it is common practice to employ the edge gage to determine the location of the outseam about the forepart of the shoe but to retract the edge gage from engagement with the outsole while sewing along the shank so that the outsole may be pressed against the machine and tilted sufficiently for proper insertion of stitches. In tilting the shoe there is danger of severing the thread of the inseam 30 through intersection with the line of outsole stitches being inserted and to avoid this, according to the disclosure of the patent, the edge gage is moved to an intermediate position while sewing along the shank of the shoe.

Referring more particularly to Fig. 1, the stitch forming devices in the machine comprise a curved hook needle 32, a curved awl 34 and a shuttle 36. The work being operated upon is clamped between a work support 38 and a presser foot 40 actuated intermittently to release the work for feeding movements.

The edge gage 20 is secured to a carrier 42 pivoted at its lower end on a fixed stud 44. The carrier 42 is retained in a rearward position by a spring 46 stretched between the carrier and a part of the machine frame. To retain the edge gage in the desired position connections for actuating the carrier include a carrier actuating cam 48 secured to a vertical shaft 50 with its lower end secured to a pinion 52 meshing with a segment 54 fixedly connected with the upper end of an adjusting shaft 56. At the lower end of the adjusting shaft is pinned an adjusting arm 58 carrying a manually operable member in the form of a handle 60.

The adjusting arm 58 is capable of limited movement with the adjusting shaft 56 while adjusting the edge gage forwardly or rearwardly. For limiting its movement and that of the edge gage, the arm has projecting from its hub a pair of oppositely directed lugs through which are threaded a pair of set screws 62 and 64 (see Fig. 6). The set screws 62, 64 engage shoulders on an enlargement 66 of a bracket 67 on the machine frame projecting downwardly from an integral bearing in the bracket which bearing supports the adjusting shaft 56. To retain the adjusting arm and shaft 56 frictionally in position after being moved, the bearing for the shaft is slotted and is clamped yieldingly against the shaft by a screw 68. As thus far described, the construction of the present machine is similar and the mode of operation is generally the same as in the prior patented machine.

The edge gage adjusting connections of the prior patented machine are so arranged that it is impossible to shift the edge gage from one extreme position to the other without stopping at the intermediate position. To do this the patented machine is provided with locking means requiring movement of a secondary arm carried by the main manual adjusting handle to unlock it. In some instances such an arrangement is undesirable, particularly when the type of work operated upon may be sewed without the use of a third edge gage position.

The actuating mechanism for the edge gage of the present invention comprises the arm 58 and other connections therewith, arranged to per-

mit manual adjustment of the edge gage 20 to any of three positions selectively without preventing continuous movement of the gage from one extreme limiting position to the other extreme position in opposite directions, stopping at the intermediate position not being required. Also the present edge gage actuating connections are arranged to eliminate the intermediate stopping position entirely by a readily actuated member. Accordingly, the means for stopping movement of the manual adjusting handle at an intermediate position of the edge gage 20 is determined yieldingly rather than by a positive lock, a yielding detent permitting continuous movement of the edge gage between extreme limiting positions if desired and providing a construction in which the detent may readily be adjusted to inoperative position.

In one form of the yielding stopping detent for the edge gage controlling connections, a recessed crossbar 70 extending at right angles to the adjusting arm 58 is connected to the undersurface of the arm. As best shown in Fig. 11, the recess, indicated at 72, of the crossbar receives the upper end of a spring-pressed plunger 74 mounted for vertical sliding movement in a block 76 secured to one end of a strut 78 projecting substantially parallel to the adjusting arm 58. The lower reduced end of the plunger extends through a coil spring 80 (Fig. 11) confined within the block 76 and through the lower surface of the block. Below the block 76 the end of the plunger is threaded and carries a pair of cheek nuts 82 acting to limit the upward movement of the plunger and to restrain the plunger in an inoperative position if required.

To adjust the position of the plunger so that the intermediate position of the edge gage and its connections may be changed to suit the operating requirements of the machine and the work, the block 76 has a horizontal groove engaging a tongue 84 (see Fig. 10) on the forward end of the strut 78. To hold the block in place the block is slotted to receive a clamping screw 86 entering into threaded relation with the end of the strut. For adjusting the position of the block on the strut the block has a threaded opening engaged by the end of an adjusting screw 88 passing through a lug on the strut, a collar 90 being secured to the screw to prevent lengthwise displacement on the lug of the strut.

To secure the strut 78 in fixed position on the machine frame the enlargement 66 on the bracket 67 has a pair of threaded openings 92 engaged by screws 94 fastened through the strut 78. Between the screws 94 is a dowel pin 96 engaging the enlargement 66 and the strut.

In the most rearward position of the edge gage the set screw 64 engages the enlargement 66 and the cam 48 is at the limit of its counterclockwise rotation as in Fig. 6. When the adjusting arm 58 is moved to bring the recess 72 into engagement with the plunger 74 neither set screw 62 or 64 engages the enlargement 66 and the edge gage is moved to its intermediate position by the cam 48, as in Fig. 7. When the edge gage is at the limit of its forward movement the set screw 62 engages the enlargement 66 and the cam 48 is at the limit of its clockwise rotation as in Fig. 8.

In another form of the invention illustrated in Figs. 12 to 17, inclusive, a similar arrangement of edge gage mechanism is provided with connections comprising an adjusting arm 98 actuated in a manner similar to that in the embodiment of the invention already described. The adjust-

ing arm 98 is of the same construction and mode of operation as that in the machine disclosed in United States Letters Patent No. 2,271,611, granted February 3, 1942, upon application of Fred Ashworth and Carl F. Whitaker. The adjusting arm is fulcrumed on a relatively fixed stud screw 100 and instead of being coupled with a segment 54 as in the previous embodiment, an extension of the arm 98 carries a pin 102 entering into a slot in a cross slide 104. The slide 104 is mounted for forward and rearward movement on a guide block 106 secured to the frame of the machine and on the slide is adjustably mounted a rack 108, the teeth of which engage those of a pinion 110 (see Fig. 15) mounted at the lower end of a vertical adjusting shaft 112. The upper end of the shaft 112 carries an adjusting eccentric 114 acting within a slot in a slide 116 to which an edge gage 118 is secured, the arrangement being such that as the eccentric is rotated the edge gage is moved forwardly and rearwardly. To limit the rearward movement of the edge gage the slide 104 has a laterally projecting lug through which passes a set screw 120 engaging a lug on the guideway block 106. To limit the forward movement of the edge gage the adjusting arm 98 carries a set screw 122 which engages a lug on a relatively fixed arm 124.

To stop movement of the edge gage at the intermediate position in this embodiment of the invention a recess 126 is formed along the under-surface of the slide, and the recess is engaged by the upper end of a spring-pressed plunger 128 slidably mounted for vertical movement in a passage formed within the guideway block 106. For changing the intermediate position of the edge gage the position of the rack 108 is adjusted on the slide 104. For this purpose, the rack is secured to the slide by a clamp screw 130 passing through a slot in the rack and entering into threaded engagement with the slide. Relative movement is imparted to the rack on the slide by rotation of a thumb screw 132 threadedly engaging an opening in the rack and having its enlarged head projecting into a groove in the upper surface of the slide, as best shown in Fig. 17.

To render the plunger 128 inoperative so that uninterrupted movement forwardly and rearwardly may be imparted to the edge gage, the plunger 128 has projecting forwardly from it a pin 134 extending through a slot 136 in the guideway block 106. The slot 136 is of a bayonet shape provided with an undercut latching surface 138 beneath which the pin may be moved after the plunger is depressed. When the pin engages the latching surface of the slot 136 the detent plunger is held out of engagement with the slide 104 and the edge gage may be moved freely to either limit forwardly or rearwardly. This same construction also is applicable to the construction of Figs. 12 to 17 inclusive, to restrain the plunger 74 in inoperative position as an alternative to the use of the check nuts 82.

The nature and scope of the invention having been indicated and a particular embodiment having been described, what is claimed is:

1. An outsole shoe sewing machine having a work support, a needle, an edge gage, a manually operated member mounted for movement during sewing operations, connections between the member and the edge gage to move the gage and means for limiting the movement of the edge gage to either of two extreme positions, in combination with means for stopping movement of the connections yieldingly at a third position be-

tween the extreme limiting positions of the gage comprising a spring-pressed detent acting on the connections, and means for restraining the detent in inoperative position against the pressure of its spring to enable free operation of the gage moving member past its third position.

2. An outsole shoe sewing machine having a work support, a needle, an edge gage, a manually operated member mounted for movement during sewing operations, connections between the member and the edge gage to move the gage and means for limiting the movement of the edge gage to either of two extreme positions, in combination with means for stopping movement of the connections yieldingly at a third position between the extreme limiting positions of the gage comprising a spring-pressed detent acting on the connections, and means for latching the detent out of action to enable free operation of the gage moving member past its third position.

3. An outsole shoe sewing machine having a work support, a needle, an edge gage, a manually operated member, an adjusting arm connected to the member for moving the edge gage during sewing operations, and means for limiting the movement of the adjusting arm to either of two extreme positions, in combination with means for stopping movement of the adjusting arm at a third position between the extreme positions comprising a recessed bar on the adjusting arm, a fixed strut projecting substantially parallel to the arm, and a spring-pressed plunger on the strut engaging the bar to enter the recess therein at said third position.

4. An outsole shoe sewing machine having a work support, a needle, an edge gage, a manually operated member, an adjusting arm connected to the member for moving the edge gage during sewing operations, and means for limiting the movement of the adjusting arm to either of two extreme positions, in combination with means for stopping movement of the adjusting arm at a third position between the extreme positions comprising a recessed bar on the adjusting arm, a fixed strut projecting substantially parallel to the arm, a block secured to the strut and arranged for adjustment in the direction of movement of the arm, and a spring-pressed plunger carried by the block to engage the bar at said third position of the adjusting arm.

5. An outsole shoe sewing machine having a work support, a needle, an edge gage, a manually operated member, an adjusting arm connected to the member for moving the edge gage during sewing operations, and means for limiting the movement of the adjusting arm to either of two extreme positions, in combination with means for stopping movement of the adjusting arm at a third position between the extreme positions, comprising a recessed slide connected to the arm, a guideway block on which the slide is mounted, and a spring-pressed plunger in the guideway block engaging the recess in the slide at said third position of the adjusting arm.

6. An outsole shoe sewing machine having a work support, a needle, an edge gage, a manually operated member, an adjusting arm connected to the member for moving the edge gage during sewing operations, and means for limiting the movement of the adjusting arm to either of two extreme positions, in combination with means for stopping movement of the adjusting arm at a third position between the extreme positions comprising a recessed slide connected to the arm, a guideway block on which the slide is mounted, a

spring-pressed plunger in the guideway block engaging the recess in the slide at said third position of the adjusting arm, and a pin projecting from the plunger arranged to be engaged with an undercut latching surface of the block to hold the plunger out of engagement with the slide.
